UNITED STATES PATENT OFFICE.

HARNEY H. JAMES, OF LOS ANGELES, CALIFORNIA.

COMBINATION SATCHEL, CART, AND CAMP-STOOL.

1,081,670.

Specification of Letters Patent. Patented Dec. 16, 1913.

Application filed May 20, 1913. Serial No. 768,824.

To all whom it may concern:

Be it known that I, HARNEY H. JAMES, a citizen of the United States, residing at Los Angeles, in the county of Los Angeles 5 and State of California, have invented certain new and useful Improvements in Combination Satchels, Carts, and Camp-Stools; and I do hereby declare the following to be a full, clear, and exact description of the 10 invention, such as will enable others skilled in the art to which it appertains to make and use the same.

This invention relates broadly to traveling bags of the convertible type, and as its 15 principal object contemplates the provision of a device of this character which may be readily converted from an ordinary traveling bag into a wheeled baby carriage, or into a modified form of camp stool.

20 A further object is to construct this invention with such regard to proportion, number and arrangement of parts that it may be cheaply manufactured and will be durable and efficient in its action.

25 The above and additional objects are accomplished by such means as are illustrated in the accompanying drawings, described in the following specification and then more particularly pointed out in the claims which 30 are appended hereto and form a part of this application.

With reference to the drawings, wherein I have illustrated the preferred embodiment of my invention as it is reduced to practice, 35 and throughout the several views of which similar reference numerals designate corresponding parts: Figure 1 is a side elevation of the satchel or hand bag, illustrating the various adjustable elements in their folded 40 position; Fig. 2 is a top plan view with the hinged covers removed; Fig. 3 is a side elevation with the various elements of the satchel arranged to permit the utilization of the satchel as a baby cart; Fig. 4 is an end 45 view of the various elements in folded position; Fig. 5 is a similar view with the end covers partially opened; Fig. 6 is a section on the line 6—6 of Fig. 2; Fig. 7 is a detail view of the device employed as a supporting 50 leg when the satchel is used as a baby cart; Fig. 8 is a detail view of the clamping device employed in securing the supporting leg in adjusted position; Fig. 9 is an edge elevation of the device shown in Fig. 8.

55 Proceeding now to the description of the drawings, the numeral 1 designates as an

entirety the body portion of the satchel or grip. This satchel is of the ordinary construction, having a leather or fabric covering arranged on a steel frame, the side members of which are designated by the numerals 2 and 3, and the end members of which are designated by the numerals 4 and 5. A pair of hinged covers 6 and 7 are mounted on the satchel 1 in the customary manner, 60 and are provided with the ordinary grip handles 8 and 9.

A U-shaped handle 10, which may be formed of strap iron, wood, or any other suitable material, is pivoted at its terminals, 70 as at 11, adjacent one end of the satchel and on the side walls thereof. The handle 10 is designed to be swung on its pivots 11 into a position of rearward extension from the member 1, as illustrated in Fig. 3. As a 75 means for holding the handles in the desired position with relation to the body of the satchel, there have been provided a pair of spring clips 12 and 13, the operation of which will be apparent by reference to 80 Fig. 4.

The supporting leg of this invention includes a substantially U-shaped frame, illustrated in Fig. 7. This frame includes the side bars 14 and 15, which are connected adjacent one terminal by a cross bar 16, secured in the usual manner by bolts, rivets, or any other suitable fastening means, as at 85 17. A pair of inwardly extending laterally projecting stub shafts 18 and 19 are carried 90 by the members 14 and 15, respectively, for a purpose to be next described.

The stub shafts 18 and 19 are journaled in the central apertures 20 of a pair of bearing plates 21, as illustrated in detail in Fig. 4. 95 The members 21 are bolted, or otherwise secured, as at 23, to one end wall of the satchel, and are each provided on their outer faces with the two grooves 24 and 25, which respectively extend in parallel relation to the longitudinal and vertical axes of the satchel. The members 14 and 15 are made of resilient metal. It will be observed, by reference to Fig. 4, that the members 14 and 15 are designed to be secured in adjusted position by being sprung into either of the two grooves 100 24 and 25. When the supporting legs are employed as supporting legs for the baby carriage they are arranged in the groove 24.

The wheel members employed in converting the satchel into a baby carriage are two in number and are arranged one on each side 110

of the end of the member 1, remote from the supporting legs. The steel frame of the satchel is shaped to produce substantially rectangular housings 26 designed to receive the wheels. The two wheels are identical in construction and it will, therefore, be necessary to describe only one of them in detail. The wheel 27 is journaled in the usual manner between the free ends of the fork 28, the fixed terminal of which is pivoted, as at 29, within the housing, and carries a sector brace member 30 pivoted to one arm of the fork, as at 31. In folded position the wheel 27 and the fork 28 are disposed within the housing 26 and are hidden from view, the member 30 being grippingly engaged by a leaf spring 32 secured to the inner wall of the housing in any desired manner. As a means for bracing the fork 28 in extended position, there is provided a laterally extending lug 33 secured to the inner wall of the housing and disposed to engage a notch formed in the member 30, adjacent the free end thereof. An expansive helical spring 34 is secured at one terminal to the member 28, and at the other to the brace 30, being thus disposed to normally hold the member 30 in engagement with the member 33.

In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion, and arrangement of parts may be resorted to, when required, without sacrificing any of the advantages of my invention, as defined in the appended claims.

What is claimed is:

1. A satchel adapted to be employed as a camp stool or a baby carriage, said satchel including a metallic frame, a covering for said frame, a U-shaped member pivoted at one end of said metallic frame and adapted to be secured in a position of parallel relation to the longitudinal or vertical axis of the satchel, a U-shaped handle pivoted on said satchel and normally disposed for engagement with the two sides and one end wall thereof, said handle being adapted to be swung into a position of longitudinal ex-

tension from the satchel when the device is employed as a baby carriage, a pair of spring clips for holding said handle in extended position, a pair of wheels arranged on each side of one terminal of the said steel frame, a substantially rectangular housing formed in each side of said steel frame, a fork for each of said wheels, each fork being pivotally mounted in one of the said housings, and a spring pressed bracing arm for holding said fork in an extended position, a laterally extending lug mounted within the housing and arranged for engagement with a notch formed in said bracing arm, said wheel, fork and bracing arm being adapted to be disposed interiorly of the said housing when the satchel is employed in its normal capacity.

2. In a device of the character described, the combination with a metallic frame having a covering therefor, of a U shaped member pivoted at one end of said metallic frame, a substantially rectangular housing formed in each side of said frame, a fork pivotally mounted within each of said housings, a wheel secured to each of said forks and means for locking said wheel within said housing, comprising a curved arm secured to each of said forks, a spring secured to each of said arms and said forks and a lug formed within said housings.

3. In a device of the character described, the combination with a metallic frame having a covering therefor, of a U shaped member pivoted at one terminal of said frame, a pair of spring clips, a substantially rectangular housing formed in each side of said frame, a fork pivotally mounted within each of said housings, a wheel secured to each of said forks and means for locking said wheels within said housings, comprising a curved arm secured intermediate the ends of each of said forks and provided with a notch adjacent its free terminal, a spring secured to each of said arms and said forks and a laterally extending lug formed in each of said housings adapted for engagement with the notch in said arm.

In testimony whereof I affix my signature in presence of two witnesses.

HARNEY H. JAMES.
